UNITED STATES PATENT OFFICE.

JOHN PFENDNER, OF CHICAGO, ILLINOIS, ASSIGNOR TO SAMUEL BUSNAK, OF CHICAGO, ILLINOIS.

COMBINED DAVENPORT AND BED.

Application filed September 2, 1919. Serial No. 321,081.

To all whom it may concern:

Be it known that I, JOHN PFENDNER, a citizen of Austria-Hungary, and a resident of Chicago, in the county of Cook and State of Illinois, have invented certain new and useful Improvements in a Combined Davenport and Bed, of which the following, when taken in connection with the drawing accompanying and forming a part hereof, is a specification.

This invention relates to a convertible davenport and bed.

Among the objects of the invention are to obtain a combined davenport and bed which is readily changed from a davenport to a bed, and back again; to obtain a construction which, when the several parts and members are in position forming a davenport, gives no suggestion that the device is convertible into a bed; to obtain a construction which a woman or well grown child can easily and quickly convert from a davenport to a bed, and also from a bed to a davenport; to obtain a construction which, when the parts thereof which form a bed are in position forming said bed, the parts forming a davenport are in position to be well protected from injury, soiling or defacing; and the parts forming the bed will form a substantially full sized one, with the members thereof held rigidly and firmly in place, with no liability to collapse or change their relative positions; and which will permit as rough usage thereto as an ordinary bed, with no liability of injury thereto; which will present a bed of suitable height, open in appearance, and not suggestive to the occupants thereof its convertibility, or a feeling of restriction and suffocation. Further objects are to obtain a convertible davenport and bed which in being converted to the other form thereof, the seat and back being in a vertical plane as above recited, requires a single operation, the several parts and members being so connected together as to require no attention or care on the part of person operating the device.

In the drawing referred to,

Fig. 1, is a perspective of a construction embodying the invention with certain parts and members in position for use as a bed, with a portion of one end removed to expose movable parts to view.

Fig. 2, is a side elevation, with one end

of the davenport frame removed, and with the several parts and members of the device in the same position as in Fig. 1, the broken lines in said figure indicating the mattress.

Fig. 3, is a top plan view of one side of the bed construction and one end of the davenport frame, the members thereof being in the same position as is illustrated in Figs. 1 and 2.

Fig. 4, is a side elevation of the movable bed members on one side of the bed, said members being midway between an open and a closed position.

Fig. 5, is a side elevation, with one end of the davenport removed and with the bed members in a closed position, the device being in condition for use as a davenport.

Fig. 6 is a perspective of some of the movable bed members, illustrating the manner of pivotally joining the side members of the bed frame.

Fig. 7, is a perspective of additional side members of the bed frame showing the pivotal attachment of a leg member thereto.

A reference character applied to designate a given part indicates said part throughout the several figures of the drawing, wherever the same appears.

A represents a frame suitable for use with the combined davenport and bed which is illustrated in the drawings, and comprises the ends *a*, *a*, the connecting bar *a*¹, and the diagonally extending straps or braces *A*¹. *A*² represents the bed box of frame A, which is removably attached to ends *a*, *a*, by screws or bolts *a*² and butterfly nuts *a*³. B represents the seat of frame A which is fulcrumed on pivots *b*, *b*. *B*¹, *B*¹, represent curved members which are attached to the ends of seat B, as by screws or bolts *b*¹, *b*¹, and *B*², *B*², represent standards which are attached to the ends of box *A*² by screws *b*². Fulcrums *b*, *b*, of seat B extend through standards *B*², *B*², and curved members *B*¹, *B*¹.

*b*³ represents bolts in one end of curved member *B*¹ which are in position to come in contact with the back C when the several parts and members are in the position as illustrated in Fig. 5, that is to form a davenport, and at said time forcing the lower end of said back forward, into contact with the rear edge of seat, B.

Said back C is secured by hinge *C*¹ to top rail, *C*², said rail being attached to ends *a*, *a*. It will be observed when the seat B is turned

- on pivot b into a substantially vertical plane, the face of said seat comes into contact with the face of back C, and forces said back into a substantially vertical plane, also, as is well 5 illustrated in Fig. 2 of the drawings. When seat B and back C are in said vertical planes the diagonally extending straps or braces A¹ limit the backward angular movement of said back.
- 10 The foregoing description of the frame adapted to coact with the hereinafter described and claimed invention is recited to make clear the relation of said invention to said frame.
- 15 The bed comprises a frame to which a spring mattress is secured, in the ordinary way; said mattress forming no part of the invention is not illustrated. The bed frame consists of a plurality of irons which are 20 pivotally joined, to permit the folding of the bed from the position illustrated in Figs. 1, 2 and 3, into the bed box A², as is illustrated in Fig. 5.
- 25 D, D¹ represent the head and foot rails, which are made of angle iron, and bent at right angles near the ends thereof, to form a part of the side rails; the remainder of the side rails consists of angle irons having the reference characters E, E¹ and F applied thereto. Said members D, D¹, E, E¹ and F being pivotally joined, as is particularly illustrated in Fig. 6 of the drawings. All of said joints comprise the same members, and hence the lettering thereof in said Fig. 6 is 30 adhered to throughout the several figures, and for all said joints. e, e, represent members which are attached to the end of one of the meeting irons, by rivets e¹, e¹, and to the other of said meeting irons by pivot e². The 35 pivoted one of the joined angle irons is rounded at the end of the vertical member thereof, as at f, Fig. 6; and said joint is so made that the horizontal members of said angle irons abut against each other as at f¹.
- 40 The members F, F, on opposite sides of the bed are joined by the pivotally attached cross member F¹, (see Fig. 3, for one end of said member), f² representing the pivot, which is rigidly secured to said member F by rivets f³. F² represents a cross member which is rigidly attached, by rivets f⁴ to irons E¹, E¹, on opposite sides of the bed. G, G¹, represent levers which are pivotally joined by pin or bolt g. Lever G is provided at one end thereof with slot g¹, and d¹ represents a pin or bolt which is rigidly secured in member D of the bed frame, to move easily in said slot. g² represents a bolt which is rigidly secured in lever G. G² represents a standard which is rigidly secured to the bed box A², and which is provided with a curved track g³, on which the bolt g² travels when the bed is being opened or closed. When the bed is opened the bolt g² 60 rests on the upper end of standard G², and G³ represents a keeper member attached to said standard, between which and the top of said standard said bolt is retained. The lever G¹ is pivotally attached at one end thereof to the lever G, as recited, and is pivotally attached, at the other end, to member F of the bed frame, by pivot or bolt g⁴. H represents legs which are secured by rivets h, h, to the pivoted member H¹, said member H¹ being pivoted between members e, e, 70 of the joint between members D¹ and E¹, by pivot h¹, said members e, e, at this joint being L-shaped to permit said pivoting. Said member H¹, is pivotally attached to lever H², by pivot or pin h². Lever H² is pivotally attached, by pin or bolt h³, to iron F of the bed. I represents a foot board, which is pivotally mounted on the standards I¹, by pivots I², said standards being riveted to the vertical web of iron D¹, by rivets i, i. I³, I³, represent springs which yieldingly hold foot board I in the position illustrated by the full lines in Figs. 1, 2, and 3, and also in the position illustrated in Fig. 2. The mattress X, which is indicated by broken lines in Fig. 2, is held in place by said foot board I being turned down thereonto, as is indicated by broken lines in said figure, when the bed is folded into bed box A².
- 75 J represents a subframe which is fulcrumed at j on standard J¹, said standard being rigidly secured to bed box A² by rivets J¹. Said subframe is U-shaped, member J³ thereof extending across the bed and serving as a bar or handle by means of which the bed is operated. Said subframe is provided with a standard J², rigidly secured thereto by rivets j², j², (on both sides of the bed), and the irons E, E, are provided with standards, J⁴, J⁴, rigidly secured thereto by rivets j⁴, j⁴, and pivotally connected to standards J², J², by bolts J⁵, J⁵. K represents a lever which is pivoted at one end on standard J¹, by pin or bolt k, and at the other end to leg L, of the subframe J, by pin or bolt k¹. The legs L, (one on each side of the bed) are pivotally attached to subframe J by pins or bolts l, l. M, (Figs. 3, 6 and 7), represents apertures in the horizontal members of the irons forming the rails of the bed, to which members of the spring are attached in the ordinary way.
- 80 Attention is directed to the function of levers G, G¹, being two fold; first, as the bed is folded into the bed box said levers turn irons D on pivots e², e², of the connection which joins it to irons E, E, from the position in which it is illustrated in Figs. 1, 2, 3 and 4, into the position in which it is illustrated in Fig. 5; and secondly, when said levers are in the position in which they are illustrated in said figures, they co-act with the abutting ends of the horizontal members of irons E, E, and F, F, maintaining said irons F, F, in horizontal planes.
- 85 90 95 100 105 110 115 120 125 130

The subframe J is turned from its position, when the bed is opened, through an angle of 180° , in closing the bed into bed box A²; and hence, standard J² which extends upward from said subframe, when the bed is open, extends downward therefrom when the bed is closed, and irons E, E, of the bed frame, not being moved to any considerable extent from a horizontal plane when the bed is being opened or closed, the standard J⁴, on said irons E continuously remains in a substantially vertical plane; and hence, when the bed is open the distance of irons E, E, (and the entire bed frame), from the subframe, is the height of the standard J² less the height of standard J⁴ and when the bed is closed the distance between said irons E, E, and said subframe is the height of standard J² plus the height of standard J⁴.

20 The above operation lowers the bed well into the bed box A² in closing it.

The lever K being fulcrumed on bolt *k* in the same horizontal plane as is said subframe fulcrumed (on bolt *j*), turns leg L from the vertical plane supporting one end of said subframe when the bed is open, as in Figs. 1, 2 and 3, into a substantially horizontal plane. When the bed is closed, as is illustrated in Fig. 5; said subframe being above the bed, the cross bar J³, of said subframe, is in convenient position to grasp and partially open the bed, say, into the position illustrated in Fig. 4. At said time the cross bar F² is in position to be conveniently grasped to complete the opening of the bed.

I claim;

1. In a combined davenport and bed, a davenport frame, and a standard rigidly secured to said frame, said standard provided with a curved track on one side thereof, in combination with a bed frame consisting of a head and a foot rail and side rails, said side rails comprising a plurality of angle irons and means to pivotally join adjacent ends thereof, levers pivotally joined, one of said levers pivotally attached to one of said angle irons, and the other provided with a slot, an abutment, (d'), rigidly secured to an additional one of said angle irons and movable in said slot, and an additional bolt rigidly secured to said slotted lever and adapted to co-act with the upper end and curved track of said standard.

2. In a combined davenport and bed, side rails respectively consisting of a plurality of angle irons, means to pivotally join adjacent ends thereof, levers pivotally joined, one of said levers pivotally joined to one of said angle irons on each side of said bed and the other provided with a slot, a bolt rigidly secured to said last named lever, and bolts in one of the end ones of said angle irons movable in said slot, in combination with standards respectively provided with a curved side, said bolts in said levers ar-

ranged to co-act with the ends and curved side of said standards, and a pivoted subframe, standards on said subframe, standards on corresponding ones of said angle irons, and bolts pivotally joining said standards.

3. In a combined davenport and bed, side rails respectively consisting of a plurality of angle irons, means to pivotally join adjacent ends thereof, L-shaped members pivotally joined to one of the end ones of said angle irons, legs attached to said L-shaped members and to corresponding ones of said angle irons, and levers pivotally joined to said L-shaped members, in combination with levers pivotally joined, one thereof pivotally joined to an additional one of said angle irons and the other provided with a slot and a bolt rigidly secured thereto, bolts in the remaining one of the end ones of said angle irons movable in said slots, standards respectively provided with a curved side, said bolts in said slotted levers arranged to co-act with the ends and curved sides of said standards.

4. In a combined davenport and bed, a collapsible bed frame the side rails whereof include a plurality of pivotally connected angle irons, means to support said angle irons in a horizontal plane, levers pivotally joined, one of said joined levers pivotally connected to the vertical member of the midway ones of said angle irons and the other of said joined levers provided with a slot, an abutment, (g²), to said slotted lever, and an abutment, (d'), on the end one of said angle irons at one end of said bed movable in said slot, in combination with a standard provided with a curved side and with a substantially horizontal upper end, said joined levers and the abutment on the slotted one thereof in spaced relation to the curved side and horizontal upper end of said standard, so that, the angle iron provided with said abutment which is in said slot, and the angle iron pivotally attached thereto being in a horizontal plane, the turning of said subframe an angular distance of 180° and into a horizontal plane, moves the abutment on said slotted lever along said curved side and on to said horizontal end of said standard.

5. In a combined davenport and bed, a frame and a box in said frame, in combination with a collapsible bed frame and a subframe, said bed frame comprising side rails which respectively include a mid-way member, additional members pivotally connected to the ends of said mid-way members, and end members pivotally connected to said additional members, and a pivotal connection between corresponding ones of said additional members and said subframe, levers pivotally connected, one of said levers pivotally connected to said mid-way member and the other provided with a slot and

connected to an end member by an abutment in said slot, an L-shaped member pivotally connected to the other end member, and an additional lever pivotally connected to

5 said mid-way member and to said L-shaped member, said pivotal connections being in spaced relation to automatically position said mid-way and additional members in

parallel vertical planes when said bed frame is collapsed, and to position all the members of said side rails in the same horizontal plane when said bed frame is extended. 10

JOHN PFENDNER.

In the presence of—

SAMUEL RUSNAK,

CHARLES TURNER BROWN.
